Application April 29, 1946, Serial No. 665,703

6 Claims. (Cl. 209—464)

1

This invention relates to classifiers in which solid particles are suspended in a body of liquid, usually water, in which the particles are separated by settling action according to size. The coarser solids, commonly referred to as sands, which settle out of the liquid, are removed therefrom by mechanical means, while the finer particles, commonly referred to as fines or overflow product, are left in suspension to be carried away with the liquid, usually by means of an overflow launder. Such classifiers are commonly used in handling ores during metallurgical operations, being frequently operated in closed-circuit with a ball mill or other grinding apparatus, but it will be understood that the classifier of the present invention may be used for any desired purpose where the classification of solid materials according to size is desired.

The present invention is concerned particularly with classifiers of the belt drag type, in which settled coarser solids or sands are removed from the bottom of the classifier tank by means of an endless belt provided with drag blades or rakes which drag the settled solids upward along an inclined bed or deck to a point of discharge above the liquid level.

One of the principal objects of the invention is to provide a belt drag classifier which will produce a more effective classifying action than belt drag classifiers heretofore employed.

Another important object is to provide a classifier of relatively low cost, both in its construction and also in its operation and maintenance.

A further object is to provide a belt drag classifier in which the belt may be made of any desired width to obtain the desired capacity, without adversely affecting the classifying action.

A further object is to provide a drag classifier capable of elevating the settled coarse solids, or sands, along an inclined bed of steeper slope than other types of classifiers, whereby the sands may be raised to the height required in large closed-circuit ball mill-classifier installations in a classifier of moderate length and without requiring the use of auxiliary pumping equipment.

A further object is to provide a drag classifier employing a belt provided with rakes for elevating sands along an inclined bed, in which a substantial portion of the sands are carried out of the liquid body or pool on the surface of the belt, thereby reducing the drag load on the rakes, and in which the sands carried by the belt are washed therefrom after leaving the main settling zone in such manner as to provide a high capacity together with highly effective classifica-

A further object is to provide a belt drag classifier in which the rakes operate at a relatively great depth in a relatively extended settling zone, without requiring the use of an under-water

idler pulley with its attendant difficulties in operation and maintenance.

A further object is to provide a classifier requiring materially less power for a given capacity than other classifiers.

A further object is to provide a classifier which may be started up after a forced shut-down causing an abnormal accumulation of settled solids in the settling zone, with a fully circulating load and without requiring the provision of any mechanism for lifting the rakes under such conditions.

A further object is to eliminate the necessity of providing belt-tensioning means for maintaining the belt tight on the pulleys.

A further object is to provide a belt drag classifier in which wear on the rakes or scraper blades is reduced to a minimum.

In accomplishing the above objects, as well as other objects which will be pointed out hereinafter or will be evident from the following description, I employ for the purpose of removing the settled solids or sands an endless belt which is provided with scraper blades or rakes for dragging such solids upward along the inclined bottom wall or deck of the tank, and which is also provided with a multiplicity of perforations distributed over the surface of the belt, and I provide water spray means for supplying water to the upper surface of the lower run of the belt, after the belt has left the liquid body or pool, for the purpose of washing settled solids from the upper surface of the belt through said perforations. In the preferred embodiment of the invention, the belt is not kept under tension so as to extend substantially straight between the pulleys, and the weight of the belt and rakes, together with settled solids accumulating on the lower run of the belt, causes the lower run to sag appreciably, so that the belt extends almost horizontal or slopes upward very gradually for some distance after leaving the tail pulley, and the slope increases progressively toward the sands discharge end of the tank. Furthermore, the overflow launder is preferably located at a position between the two pulleys over which the belt runs, at a position substantially above the lowest point of the belt.

The accompanying drawings illustrate a preferred form of classifier according to the present invention, and certain possible modifications thereof. Referring to these drawings:

Fig. 1 is a plan view, with parts of the upper run of the belt broken away, showing a preferred form of classifier according to this invention;

Fig. 2 is a somewhat enlarged plan view of a portion of the lower run of the belt;

Fig. 3 is a transverse sectional view on line 3—3 in Fig. 2, showing a preferred construction of the rakes;

Fig. 4 is a transverse sectional view on line 4—4 in Fig. 2, showing one of the rakes provided with a serrated lower edge for a purpose described hereinafter;

Fig. 5 is a longitudinal section of a portion of the belt, taken on line 5—5 in Fig. 2;

Fig. 6 is a vertical section of the classifier, on line 6—6 in Fig. 1;

Fig. 7 is a partial vertical sectional view of a modified form of classifier; and

Fig. 8 is a partial longitudinal section of the belt, corresponding to Fig. 5 but showing a modified arrangement of the perforations in the belt.

The classifier shown in Figs. 1 and 6 comprises a tank adapted to contain a body of liquid, generally water, having a bottom wall 1, side walls 2 and an end wall 3. Side walls 2 and end wall 3 extend upward above the liquid level indicated by the dot-dash line at L. The bottom wall 1 is inclined upward in a direction away from the end wall 3, through the major portion of its length, to provide an inclined deck D which extends from a position below the body of liquid to a position of sands discharge a considerable distance above the liquid level at the opposite end of the tank, as indicated at 4.

A continuous flexible belt 6 of rubber, rubber-covered fabric, or other suitable belting material is mounted for movement through the tank and is carried on a head pulley 7 and tail pulley 8, whose shafts are rotatably journaled in suitably mounted bearings 9 and 10, respectively. The belt 6 is preferably mounted slackly on pulleys 7 and 8, and said pulleys are preferably crowned somewhat as shown at 7' and 8' in Fig. 1 to maintain the belt in properly centered position thereon. Belt 6 is driven by means of head pulley 7 which is operated by any suitable motive power such as an electric motor 11 connected thereto through conventional speed-reducing mechanism indicated generally at 12 and 13. The driving pulley 7 is preferably slotted, as indicated at 14, so as to prevent slipping of the belt thereon.

The tail pulley 8, which acts as an idler pulley, is of relatively large diameter and extends to a position substantially below the liquid level and near the bottom of the tank, above and adjacent the lower end of the inclined deck D, while head pulley 7 is of smaller diameter and is located at a higher level, above and adjacent the upper end of said deck, so that the lower run of the belt indicated at 6a extends from a position near the bottom of the tank at the deeper portion thereof, in a generally upwardly inclined direction, to a position above the liquid level and beyond the sands discharge lip 4. The upper run of the belt, indicated at 6b, is disposed wholly above the liquid level in the tank.

Belt 6 is provided with a plurality of equally spaced outwardly projecting rakes 16 extending transversely and secured to the outer surface thereof at suitable intervals. In the lower run 6a, these rakes project below the belt, in position to scrape or drag settled solids upwardly along the inclined deck as the belt is moved in the direction indicated by the arrows at A in Figs. 5 and 6. Said rakes extend across substantially the entire width of the belt and may project somewhat beyond the edges thereof as indicated at 16a. Each of said rakes, as illustrated particularly in Figs. 2, 3 and 5, may comprise a length of angle iron 17 bolted or otherwise secured to the belt and having its middle portion bent outward as shown at 17a to conform to the crown of the pulleys. The rakes are preferably

provided with wearing blades or tips 18 removably secured thereto and projecting outward beyond the outer edges of the angle bars. As illustrated in Fig. 3, I prefer to provide a plurality of such removable wearing blades for each rake, bolted or otherwise secured to angle bar 17 in end-to-end relation, with their outer edges disposed in a straight horizontal line.

In order to reduce wear on the removable wearing blades, I prefer to provide one of the rakes, indicated at 16' in Figs. 2, 4 and 5 with wearing blades 18' having serrated edges 19 which extend beyond the edges of the other rake blades to prevent the sands from becoming unduly hardened, as described hereinafter. More than one of the rakes may, if desired, be thus provided with a serrated edge, but I have found that the provision of one of these serrated-edge blades at any position on the belt is generally sufficient for this purpose.

Belt 6 is of sufficient length, in relation to the spacing of the pulleys, to sag appreciably between said pulleys. The weight of the belt and the rakes 16, together with the sands deposited thereon as hereinafter described, causes the lower run of the belt, even though submerged beneath the liquid and subjected to an upward thrust against the rakes by the solids depositing at the bottom of the tank, to sag so that it extends almost horizontal or even slopes slightly downward after leaving the tail pulley 8 and then slopes upward, at first very gradually and then at a progressively increasing angle toward the head pulley 7. It will be seen that, because of this sagging of the belt, said belt and the rakes carried thereby are caused to follow a curved path through the tank and are submerged to a relatively great depth in a relatively extended settling zone adjacent the tail pulley and at the side thereof toward the inclined deck D.

It will also be noted that the deck D is located low enough to accommodate the sag of the lower run of the belt, said deck being disposed below the curved path of the rakes 16 resulting from the sag of the belt, and being preferably shaped to conform generally to the curvature of the belt. Thus, the upper portion D₂ of the deck is shown as inclined at a steeper angle than the lower portion D₁. From the lower end of deck portion D₁, which is adjacent the lowermost point of the belt, the bottom wall 1 is preferably inclined slightly upward, as shown at 1a, to the end wall 3.

The classifier tank is provided with a transversely extending feed launder 21 which is shown as located above the end wall 3 at the deeper end of the tank, a transversely extending overflow launder 22 located between the pulley 8 and the sands discharge end of the tank, and a transversely extending sands discharge launder 23 positioned to receive the sands discharged over lip 4. The overflow launder 22 is provided with side walls 22a whose upper edges extend horizontally across the tank and serve to establish and maintain the desired liquid level therein.

It will be seen that said overflow launder is located within the above-mentioned relatively deep extended settling zone afforded by the sag of the belt, and is above the lower portion of the lower run of the belt. The effect of the sag of the belt in increasing the depth of the settling zone at the position of the overflow launder may be seen by a comparison with the depth of settling zone that would be afforded if the belt extended straight between the pulleys, as indicated by the dot-dash line at X in Fig. 6 and the lower

edges of the rakes moved along the corresponding straight path indicated at Y.

The belt 16 is provided with a plurality of perforations or openings 25 extending therethrough and distributed over its surface. Said openings may be of any desired size and shape. Circular openings about 1" to 1 1/2" in diameter have been found satisfactory. These openings may be arranged in transverse rows, and I have shown a plurality of such rows between each two adjacent rakes, as best illustrated in Figs. 2 and 5. The number and total area of the perforations may be selected to give the best results, but I have found that the total area of perforations should generally be between about 5% and about 30% of the total area of the belt (including the perforations), and preferably in the neighborhood of 8% to 12% of the total belt area.

Suitable means are provided for supplying water or other liquid, preferably in the form of sprays, onto the upper surface of the lower run of belt 6, at a position above the point where the belt emerges from the body of liquid, that is, at a position above the liquid level L.

Said liquid supply means may comprise, for example, one or more spray pipes or headers extending transversely above the lower run of the belt, at one or more positions above the liquid level. In the drawings I have shown a pipe 27 extending across the entire width of the belt and above the upper run thereof at a position above and closely adjacent the point at which the belt emerges from the liquid, and another pipe 28 extending across and above the belt at a position further along the path thereof, each of said pipes being provided with a plurality of spaced openings as indicated at 27' and 28', respectively, so positioned and directed as to deliver water sprays in a general direction inclined downwardly and rearwardly with respect to the direction of belt travel. The water sprays delivered by these pipes are indicated in dotted lines at 29 and 30, respectively, and I have shown the pipe 27 as provided with a larger number of spray openings or orifices than the pipe 28. Pipes 27 and 28 are shown connected through control valves to a pipe 31 for supplying water or other liquid thereto. The individual valves may be adjusted to any desired quantity of liquid to the respective pipes.

While this particular arrangement and location of spray pipes has been found advantageous, it is not essential to the present invention. In some cases I may use only a single spray pipe located at either of the two positions shown or at any other desired position between the point where the belt emerges from the liquid and the sands discharge lip 4, or I may provide any desired number of spray pipes at different locations within this region.

In the operation of the classifier described above the feed, comprising solid particles and liquid, is supplied through feed launder 21 into the tank, and the liquid eventually overflows the upper edges of the side walls 22a of overflow launder 22, so as to maintain in the tank a body of liquid up to the level indicated at L. Moderate agitation of the liquid and suspended solid particles is provided by the movement of the drag belt 6 and tail pulley 8 through the liquid, but the agitation so produced is not sufficiently active to prevent gravity separation of the coarser and finer particles by settling action. The coarser particles settle toward the bottom of the tank, this settling action taking place principally in the relatively extended settling zone of relatively

great depth in the portion of the tank located generally between the tail pulley 8 and the inclined deck D. Part of the settled coarser solids are deposited on the upper surface of belt 6, while the remaining portion of these settled solids passes through the perforations in the belt and is deposited on the inclined deck, to form a bed of settled solids, whence the solids are continually removed by the rakes 16 and are moved thereby upwardly along the above said deck, out of the body of liquid. After leaving the liquid, the solids are moved by the rakes over the upper portion of the deck to permit draining of liquid therefrom back into the liquid body, and are delivered over the sands discharge lip into the sands discharge launder 23.

Some of the coarser solids or sands which are deposited on the upper surface of the lower run of the belt are carried on the belt out of the body of liquid, and are thereafter washed from the belt by the liquid sprays from pipes 27 and 28, through the perforations and into the path of the rakes 16. These sands are picked up by the rakes and discharged thereby along with the other sands, while the water from the sprays drains back into the pool in the tank. The washing action of the sprays also tends to dislodge any fine solid particles that may have been deposited with the coarser solids on the belt, and such dislodged fine particles will tend to remain in suspension in the liquid flowing down over the deck, and will thus be returned to the main body of liquid. Hence this washing action improves the separation of coarse and fine solids and contributes to the efficiency of classification. It has been found that a particularly effective de-sludging action is obtained when the sands are washed from the upper surface of the belt at a point just above the liquid pool, as by means of the liquid sprays 29 from pipe 27.

The fine solids that remain in suspension in the liquid in the settling zone are discharged with the liquid through the overflow launder 22.

It will be noted that the belt 6 extends transversely the major portion of the transverse extent of the rakes 16, and the total area of the perforations 25 is relatively small as compared to the total area thereof. Consequently, a considerable proportion of the coarser solids moving downward by gravity toward the path of movement of the rakes are caught on the upper surface of the belt and are carried out of the liquid on the belt instead of being allowed to fall to the bottom of the tank for removal by the dragging action of the rakes. This increases the capacity of the classifier and also reduces the drag load on the rakes, and also causes a considerable proportion of the coarse solids to be subjected to the washing action of the liquid sprays from pipes 27 and 28 with a resultant improvement in the efficiency of classification, as noted above.

In addition to the possible modifications in certain parts of the apparatus mentioned above, numerous other modifications may be made within the scope of my invention. For example, as illustrated in Fig. 7, the positions of the feed launder and fines overflow launder may be reversed. In this case, the feed launder 21' is shown as extending across the tank at the same side of pulley 8 as the inclined deck D and between said pulley and the sands discharge end of the machine, while the fines overflow launder 22' with its side wall 22a' which defines the liquid level in the tank is located above the end wall 3.

The other parts of the apparatus are the same as described above.

The rakes on the belt can be of any desired depth perpendicular to the surface of the belt, for example, from about three or four inches to about 10 inches or more. With relatively deep rakes, in which the flange of the angle bar secured to the belt may be relatively wide, it may be desirable to provide perforations in this angle flange and in the part of the belt to which it is secured, in order to provide more uniform distribution of the perforations over the entire surface of the belt. Such a construction is illustrated in Fig. 8, the perforations in the angle bar flanges and in the portions of the belt to which it is secured being indicated at 25a and 25b respectively.

By providing one of the rakes with a projecting serrated edge 19, as described above in connection with Figs. 4 and 5, the teeth of this rake dig into and loosen the surface of the bed of settled solids on the deck D. This prevents formation of a hard or caked surface and thus reduces the wear on the edges of the rakes.

The weight of the rakes 16 is an important factor in contributing to the desired sag of the belt and maintaining the desired relatively great depth of pool in the settling zone (below the preferred location of the overflow launder as shown in Figs. 1 and 6) regardless of tonnage handled, or size or density of feed. The angle bars 17 of the rakes may be extra heavy, for example, in installations handling a coarse high density feed, while lighter weight angles may be used when handling a fine feed of low specific gravity.

I claim:

1. In a belt drag classifier for separating solid particles suspended in a liquid, the combination comprising: a tank adapted to contain a body of liquid containing suspended solid particles, having a bottom wall providing a deck inclined upward in a direction away from one end of the tank to a position above the surface of said body of liquid; an endless belt having its lower run extending within said tank and movable upwardly along and above said inclined deck to a position above the body of liquid, said belt being provided with a plurality of transversely extending outwardly projecting rakes for moving settled solids upwardly along said deck; said belt extending transversely the major portion of the transverse extent of said rakes and being provided with a multiplicity of perforations distributed over its surface; and means for supplying liquid to the upper surface of the lower run of said belt at a position above the body of liquid, to wash solids from said upper surface through said perforations.

2. In a belt drag classifier for separating solid particles suspended in a liquid, the combination as set forth in claim 1, in which the total area of said perforations is between about 5% and about 30% of the total area of the belt.

3. In a belt drag classifier for separating solid particles suspended in a liquid, the combination as set forth in claim 1, in which the total area of said perforations is in the neighborhood of 8% to 12% of the total area of the belt.

4. In a belt drag classifier for separating solid particles suspended in a liquid, the combination comprising: a tank adapted to contain a body of liquid containing suspended solid particles, having a bottom wall providing a deck inclined upwardly in a direction away from one end of said

tank to a position above the surface of said body of liquid; an idler pulley extending within said tank above and adjacent the lower end of said inclined deck; a drive pulley located above and adjacent the upper end of said deck; an endless belt carried by said pulleys and having its lower run extending within said tank and movable by said drive pulley upwardly along and above said inclined deck to a position above the body of liquid, said belt being provided with a plurality of transversely extending outwardly projecting rakes for moving settled coarse solids upwardly along said deck; said belt extending transversely the major portion of the transverse extent of said rakes and being provided with a multiplicity of perforations distributed over its surface, and said belt extending slackly over said pulleys, whereby the weight of said belt and rakes causes the lower run of the belt to sag appreciably between said pulleys and to move in a curved path, and said deck being disposed below the curved path of the rakes resulting from said sag of the belt so as to provide an extended settling zone of relatively great depth in the tank adjacent the lower portion of the lower run of the belt; and means for supplying liquid to the upper surface of the lower run of said belt at a position above the body of liquid, to wash solids from said upper surface through said perforations.

5. In a belt drag classifier for separating solid particles suspended in a liquid, the combination as set forth in claim 4, in which said tank is provided with means for supplying solid particles and liquid thereto adjacent said one end thereof, and with a liquid overflow launder extending above the lower run of said belt and within said extended settling zone.

6. In a belt drag classifier for separating solid particles suspended in a liquid, the combination comprising: a tank adapted to contain a body of liquid containing suspended solid particles, having a bottom wall providing a deck inclined upward in a direction away from one end of the tank to a position above the surface of said body of liquid; an endless belt having its lower run extending within said tank and movable upwardly along and above said inclined deck to a position above the body of liquid, said belt being provided with a plurality of transversely extending outwardly projecting rakes for moving settled solids upwardly along said deck; said belt extending transversely the major portion of the transverse extent of said rakes and being provided with a multiplicity of perforations distributed over its surface; and liquid spray means extending across said tank above the lower run of said belt and provided with spaced orifices so positioned and directed as to deliver a plurality of liquid sprays onto the upper surface of the belt at a position above the body of liquid and in a direction inclined downwardly and rearwardly with respect to the direction of travel of the belt, to wash solids from said upper surface through said perforations.
